(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines shown in the figures that are immediately adjacent to the areas included in the claim and define unshaded regions represent the bounds of the claim. All other broken lines, including those within broken line boundaries, the display rectangle, and the tiny features extending from the bottom port onto the front and rear are directed to environment. The broken lines form no part of the claimed design.
